DISPLAY FORM

Filed Dec. 10, 1929

Inventor

Alexander Simson ~

By Clarence A. O'Brien
Attorney

UNITED STATES PATENT OFFICE

ALEXANDER SIMSON, OF RENO, NEVADA

DISPLAY FORM

Application filed December 10, 1929. Serial No. 413,096.

This invention relates to display forms, of the type particularly adapted for use in ready-to-wear clothing establishments, where suits of wearing apparel are displayed in show windows.

An important object of the invention is to provide, in a manner as hereinafter set forth, a display form of the above-mentioned character having inflatable means embodied therewith, whereby the form may be expanded to adapt the same to apparel of different sizes and to assure a proper and attractive fitting of the garment in an expeditious manner and without the necessity of using packing.

Other objects and advantages of the invention are to provide, in a manner as hereinafter set forth, a display form of the character set forth which will be simple in construction, strong, durable, efficient in its use and which may be manufactured at low cost.

The foregoing and other objects and advantages of the invention will become apparent from a study of the following specification, taken in connection with the accompanying drawings, wherein like characters of reference designate corresponding parts throughout the several views, and wherein:-

Figure 1 is a view in front elevation, partly broken away in section, of a display form constructed in accordance with this invention.

Fig. 2 is a view in front elevation of a display form constructed in accordance with the present invention, wherein inflatable sleeves are embodied therewith,

Fig. 3 is a vertical cross sectional view taken substantially on the line 3-3 of Fig. 1,

Fig. 4 is a horizontal cross sectional view taken substantially on the line 4-4 of Fig. 1.

Referring to the drawings in detail, the reference character 1 designates a hollow core or shell of any suitable material, such as wood or metal and which has the configuration of the upper portion of a human body. The lower portion of the front of

the core is recessed in the usual manner as at 2, in order that the form will not be visible when the device is in use.

The upper end of the core 1 terminates in an integral solid tap block 3, the inner side of which is provided with a threaded socket for the reception of the threaded upper end of the supporting standard 4, as best illustrated in Fig. 3 of the drawings.

A covering 5 of suitable material, such as rubberized fabric is secured to the outer surface of the core 1 by any suitable means such as an adhesive or separable snap fasteners, said covering 5 being constructed of a single piece of material which is substantially tubular in form and is open at both ends, the upper end being disposed beneath a shoulder 6 on the cap block 3.

A rubber casing or envelope 7 is then mounted over the covering 5 and also extends from a point beneath the shoulder 6 to the lower end of the core 1. A metallic cap plate 8 is mounted on the cap block 3 and has its skirt portion extending over the upper end of the casing 7. An air conducting tube 9 which is provided with a suitable check valve, has communication with the interior of the casing 7 through the medium of the branch tubes 10-10 which extend through the core 1, covering 5 and the inner wall of the casing 7 at a point where the armholes of the garment come.

In Fig. 2, the reference numeral 11 designates an inflatable sleeve form which is attached to the casing 7 and has communication therewith. The sleeves are of a construction similar to the casing 7 and may be provided with weights (not shown), in the lower ends to prevent same from swinging upwardly, when the device is inflated.

In the use of the device, the garment is mounted thereon, and the casing 7, together with the sleeve portions 11 are inflated by blowing air through the tube 9 and the branch tube 10, with the result that a very attractive and snug fit garment will be had, and all wrinkles and irregularities therein will be eliminated.

It is believed that the many advantages of a display form constructed in accord-

ance with this invention will be readily understood, and although the preferred embodiment of the invention is as illustrated and described, it is to be understood that changes in the details of construction may be had which will fall within the scope of the invention as claimed.

Having thus described my invention, what I claim as new is:—

- 10 A display form of the character described comprising a hollow core having a cap block provided with an annular shoulder, a supporting standard secured to the cap block, a tubular one-piece covering of rubberized
- 15 fabric mounted on the core having its upper end disposed to meet the shoulder on the cap block, an inflatable rubber casing constructed of a single piece of material and of substantially tubular form extending over
- 20 the rubberized covering and having its upper end disposed beneath the annular flange, a metallic cap plate mounted on the cap block and extending downwardly over the upper end portion of the casing for maintaining said casing in position on said cap block, and means for inflating the casing, said means disposed within the core.
- 25

In testimony whereof I affix my signature.

ALEXANDER SIMSON.
